UNITED STATES PATENT OFFICE.

ISAAC C. HOWLETT, OF BANGS, TEXAS.

BAG-CUTTING MACHINE.

Application filed January 3, 1922. Serial No. 526,691.

To all whom it may concern:

Be it known that ISAAC C. HOWLETT, a citizen of the United States of America, residing at Bangs, in the county of Brown and 5 State of Texas, has invented new and useful Improvements in Bag-Cutting Machines, of which the following is a specification.

The object of the invention is to provide simple and efficient means for cutting the 10 material used for shipping sacks at the proper and uniform lengths for standard capacities of the sacks under conditions serving as a means of economizing time and effort on the part of the operator while insuring uniformity in the protection of the sacks; and 15 with this object in view the invention consists in a construction and combination of parts of which a preferred embodiment is shown in the accompanying drawings, 20 wherein:—

Figure 1 is a view of a sack cutting machine embodying the invention.

Figure 2 is an end view thereof.

Figure 3 is a rear view.

25 Figure 4 is a detail view partly in section of the clutch mechanism for controlling the operation of the movable knife.

Figures 5, 6, and 7 are detail views of members of the clutch.

30 Figure 8 is an enlarged view of a portion of the shiftable member of the clutch to show the shifting or cam groove thereof.

Figure 9 is a detail section on the plane indicated by the line 9—9 of Figure 5.

35 Carried by a suitable framework 10 are the fixed and movable complementary knives 10^a and 11 of which the latter is supported by links 12 and 13 to effect a swinging movement thereof and hence a shear cut with relation to the lower blade and is yieldingly supported in its elevated or inoperative position by a spring 14. In rear of the plane of

40 these blades are the feed rollers 15 and 16, one or both of which may be toothed or provided with spurs or pegs for effectively engaging the material; the upper roller being movably supported by means of links 17 and held by gravity or other yielding force in operative relation with the lower roll, the

45 50 material for the sacks being supplied in the form of rolls or bolts indicated at 18 and held in proper position for feeding the material to the feed rolls by means of bolt hangers 19 consisting of bars having in-

turned terminal spurs 20 forming trunnions 55 for engagement with the ends of the roll or bolt of material and supported by swinging links 21. The inner ends of said bars are connected by links 22 with a rack bar 23 which furthermore is slotted as shown at 24 60 to receive a guide pin 25 at the intersection of the bars 19. Obviously by the vertical movement of the rack bar, due to the toggle connection therewith of the bars 19, the jaws may be operated to cause engagement with or disengagement from the roll or bolt. The stopper wheel 26 is arranged to engage with said rack bar and is carried by a shaft 27 having a crank arm 28 and ratchet mechanism 29 by which the rack bar may be held 70 in adjusted positions.

The operation of the movable blade is effected by means of a bell-crank lever 30 of which one arm is represented by the link 13, and a pitman 31 connected with a crank 75 wheel 32 loosely mounted upon the drive shaft 33 which is adapted to be continuously driven through power applied by means of the belt wheel 34. The crank wheel or disk 32 carries a sleeve 35 having a clutch member 36 which is adapted for engagement by a shifting clutch member 37 also loosely mounted on the shaft 33 and having an actuating spring 38 serving to impel the same toward or into engaging relation with the 80 clutch member 36. Fixed to the drive shaft 33 carries a supplemental clutch member 39 for engagement with which the shifting clutch member 37 is provided with a clutch face 40, so that when the shifting clutch member is 85 engaging relation with the fixed clutch member 39 so as to receive motion from the shaft, it is also in interlocking engagement with the clutch member 36 to communicate motion to the crank disk and hence through the 90 pitman and bell-crank or rocker 30 to the movable cutter bar or knife which is movable to its operative or cutting position in opposition to the tension of the spring 14.

Motion is communicated from the drive 100 shaft 33 to a countershaft 41 by means of a belt 42 traversing a pulley 43 on the drive shaft and one of the respectively fast and loose pulleys 44 on the countershaft under the control of a belt shifter 45, and through 105 intermeshing beveled gears 46 motion is communicated from said countershaft to the lower feed roll 15.

The shifting clutch member 37 is provided, as will be seen more clearly by reference to Figures 5 and 8, with a cam groove 47 extending peripherally and for a portion of its distance spirally thereof, with the longitudinally deflected or spiral portion 48 thereof arranged in overlapping relation with the initial end 49 and with a depressed bottom or floor as shown at 50 between which and the floor of the initial end of the groove is arranged a shoulder 51. Operating in this groove is a key 52 carried by a trigger 53 which is pivotally mounted at 54 and is of bell-crank form with a trip arm 55 arranged in the path of an armed trip 56.

When the shifting clutch member is in its closed position or is in engagement with the clutch members 36 and 39 to lock the latter to the drive shaft and thus communicate motion to the movable knife blade, the key 52 is arranged in the cam groove and follows the groove until the spirally deflected portion thereof by contact with the key moves the shifting clutch member longitudinally of the shaft against the pressure of the spring 38 to effect the disengagement of the clutch faces. This disengagement occurs and therefore the motion of the cutter blade ceases when the crank disk has made one complete revolution. The trigger which carries the key 52 is actuated by a spring 57 tending to hold the key downward in the groove, and therefore the key follows the inwardly deflected bottom of the groove at the end thereof and serves by engagement with the shoulder 49 to hold the shifting clutch member in the reversed position in opposition to the spring 38.

The spindle 58 of the trip 56 carries a worm gear 59 engaged by a worm 60 on the lower or main feed roll, so that as the latter turns and thereby feeds a definite length of the sacking material through the plane of the cutter knives, it communicates motion through the worm and gear to the trip 56 and when the arm of the latter strikes the trip arm of the trigger 53 it moves the latter in opposition to its actuating spring 57 to raise the key 52 sufficiently to disengage it from the shoulder 49 and thereby permit the spring 38 to advance the shifting clutch member to its closed position and thus cause the operation of the cutter. The advancement of the shifting clutch member again brings the key into position in the initial end of the cam groove and at the end of a revolution of the drive shaft the clutch member is again withdrawn from engagement by the action of the key on the spirally deflected wall of said groove to discontinue the movement of the cutter mechanism and permit a further length of the sacking material to be fed between the blades thereof.

A spring actuated tensioning device or

brake 61 is arranged for contact with the bolt or roll of sacking material to prevent the irregular unwinding thereof.

Having described the invention, what is claimed as new and useful is:—

1. A machine for cutting a continuous strip of material into specified lengths, having a feed roll traversed by the material, a cutter mechanism having an intermittently movable member, a rotary driving member, a clutch for connecting the cutter mechanism with the driving member, and clutch shifting means having an actuating element movable in timed relation with said feed roll, and consisting of a rotary tappet head 80 geared to the feed roll.

2. A machine for cutting a continuous strip of material into specified lengths, having a feed roll traversed by the material, a cutter mechanism having an intermittently movable member, a rotary driving member, a clutch for connecting the cutter mechanism with the driving member, and clutch shifting means having an actuating element movable in timed relation with said feed roll, the clutch having a spring actuated member with a tendency to move to closed position, and the shifting means having a lever engaged clutch retracting cam.

3. A machine for cutting a continuous strip of material into specified lengths, having a feed roll traversed by the material, a cutter mechanism having an intermittently movable member, a rotary driving member, a clutch for connecting the cutter mechanism with the driving member, and clutch shifting means having an actuating element movable in timed relation with said feed roll, the clutch having a spring closed member provided with a spiral cam, and the shifting means having a key movable radially of the clutch for engaging said cam.

4. A machine for cutting a continuous strip of material into specified lengths, having a feed roll traversed by the material, a cutter mechanism having an intermittently movable member, a rotary driving member, a clutch for connecting the cutter mechanism with the driving member, and clutch shifting means having an actuating element movable in timed relation with said feed roll, the clutch having a spring closed member provided with a spiral cam groove with its terminals in communication longitudinally of the clutch.

5. A machine for cutting a continuous strip of material into specified lengths, having a feed roll traversed by the material, a cutter mechanism having an intermittently movable member, a rotary driving member, a clutch for connecting the cutter mechanism with the driving member, and clutch shifting means having an actuating element movable in timed relation with said feed roll, the clutch having a spring closed member

provided with a spiral cam groove with its terminals in communication longitudinally of the clutch, a radial stop shoulder being disposed between the terminals of the 5 groove.

6. A machine for cutting a continuous strip of material into specified lengths having a feed roll traversed by the material, a cutter mechanism embodying an intermittently movable member, a rotary driving member, a clutch for operatively connecting the cutter mechanism with the driving member, and clutch operating means embodying a trigger, a trip for engagement with said 10 trigger and operated in timed relation with said feed roll, the clutch having a spring closed member provided with a spiral cam groove with its terminals in communication longitudinally of the stock, one extremity of the cam groove being depressed to a lower level than the connecting extremity to provide a radial stop shoulder, the trigger having a key traversing said cam groove and engageable with said shoulder for the 15 purpose specified.

20 tremity of the trigger being operatively engaged in said cam groove.

7. A machine for cutting a continuous

strip of material into specified lengths having a feed roll traversed by the material, a cutter mechanism embodying an intermittently movable member, a rotary driving member, a clutch for operatively connecting the cutter mechanism with the driving member, and clutch operating means embodying a trigger, a trip for engagement with said 25 trigger and operating in timed relation with said feed roll, the clutch having a spring closed member provided with a spiral cam groove with its terminals in communication longitudinally of the stock, one extremity of the cam groove being depressed to a lower level than the connecting extremity to provide a radial stop shoulder, the trigger having a key traversing said cam groove and engageable with said shoulder for the 30 purpose specified.

In testimony whereof he affixes his signature.

ISAAC C. HOWLETT.
